7 Claims. (Cl. 175—373)

1

The present invention relates to generators of electric oscillations of special wave forms and makes use of the properties of thermally sensitive resistance elements known as thermistors for obtaining the waves.

Thermistors have been in use for some years and are characterized by a temperature coefficient of resistance which may be either positive or negative and which is moreover many times the corresponding coefficient for a pure metal such as copper. This property renders thermistors particularly suitable for a variety of special applications in electric circuits.

Various different materials are available for the resistance element of a thermistor, these various materials having different properties in other respects; as one example, a resistance material having a high negative temperature coefficient of resistance comprises a mixture of manganese oxide and nickel oxide, with or without the addition of certain other metallic oxides, the mixture being suitably heat treated.

Thermistors have been employed in two different forms: (a) known as a directly heated thermistor and comprising a resistance element of the thermally sensitive resistance material provided with suitable lead-out conductors or terminals, and (b) known as an indirectly heated thermistor comprising the element (a) provided in addition with a heating coil electrically insulated from the element. A directly heated thermistor is primarily intended to be controlled by the current which flows through it and which varies the temperature and also the resistance accordingly. Such a thermistor will also be affected by the temperature of its surroundings and may therefore be used for thermostatic control and like purposes with or without direct heating by the current flowing through it. An indirectly heated thermistor is chiefly designed to be heated by a controlling current which flows through the heating coil and which will usually, but not necessarily, be different from the current which flows through the resistance element, but this type of thermistor may also be subjected to either or both of the types of control applicable to a directly heated thermistor.

More detailed information on the properties of thermistors will be found in an article by G. L. Pearson in the Bell Laboratories' Record Dec. 1940, page 106.

Regularly repeated oscillations having special types of wave form are required for various purposes. In particular, saw-tooth waves are commonly used in television systems for synchronization purposes, and rectangular waves are used

2

for multivibrator circuits. Such special waves are generally obtained in relaxation oscillator circuits employing gas discharge valves, or equivalent hard valve combinations. Such circuits are frequently complicated and require various power supplies for the valves, and moreover are often difficult to operate satisfactorily at very low frequencies.

The present specification describes simple circuits employing directly or indirectly heated thermistors for generating various types of wave form, such circuits not including any valves.

According to the invention there is provided a generator of periodically varying electric currents comprising two or more thermistors, and an electromagnetic switch having an operated position for each thermistor in which position it connects the corresponding thermistor to a source of heating current, means being provided to enable the thermistor to vary a current for operating the switch during the heating period so that when the operating current reaches a predetermined value the switch moves to another operated position.

25 The invention will be more clearly understood from the following detailed description of embodiments with reference to the accompanying drawing in which:

Fig. 1 shows a schematic circuit diagram of a 30 generator of waves of the saw-tooth type and employing indirectly heated thermistors.

Fig. 2 is an alternative to Figure 1 employing directly heated thermistors.

Fig. 3 is a schematic circuit diagram of a 35 generator of waves more of a rectangular type employing directly heated thermistors; and

Fig. 4 shows wave-form diagrams for explaining the operation of Figure 3.

In this specification it is to be understood 40 that all resistances not referred to as thermistors are of the usual type in which the resistance value does not depend appreciably on the current through the resistance.

Fig. 1 shows an arrangement for producing 45 waves of a saw-tooth type. A is a differential relay or like type of switch having two equal windings w_1 and w_2 . The relay is provided with two sets of change-over contacts a_1 and a_2 operated by currents in the windings w_1 and w_2 . The

50 relay should preferably be designed so that a current in winding w_1 in the direction of the arrow closes the upper contact of a_1 and the lower contact of a_2 , while current in the direction shown in the winding w_2 closes the lower contact of a_1 and the upper contact of a_2 . If currents are simultaneously present in both wind-

ings, then the contacts corresponding to the preponderating current will be closed. The relay should be adjusted so that a change-over does not occur until the difference between the two currents exceeds a predetermined value the relay maintaining its initial setting until the predetermined value of difference current is established. Thus once a change-over occurs the switched positioned is maintained until the difference between the currents in the two windings reaches the predetermined value, and is of a direction to cause change-over to the other position.

The relay windings w_2 and w_1 are respectively connected in series with the resistance elements R_1 and R_2 of two indirectly heated thermistors T_1 and T_2 and two resistances R_5 and R_6 to a battery or other suitable constant potential source E_1 . The heating coils r_1 and r_2 of the thermistors T_1 and T_2 are connected across the battery E_1 through the upper and lower contacts respectively of a_1 . The output terminal 1 is connected to the junction of R_5 and R_6 , and preferably also to earth, and the other output terminal 2 is connected to the moving spring contact of a_2 , whereby it may be switched alternately to R_5 and R_6 .

It will be assumed that the upper contact of a_1 and low contact of a_2 are closed as shown when the battery is first switched on. The thermistors, being cold, will have a high resistance (assuming that they have a negative temperature coefficient of resistance) so the voltage drop across R_5 and R_6 will be small. A low voltage will therefore be obtained at the output terminals. The currents in the two windings w_1 and w_2 being at first equal there will be no force tending to change over the contacts a_1 and a_2 .

The thermistor T_1 now heats up on account of the current which flows through its heating coil r_1 , and the resistance R_1 falls, thereby increasing the current in the circuit containing w_2 and R_5 . The output voltage at terminals 1 and 2 rises at a rate determined by the characteristic of the thermistor. When the current through w_2 exceeds that through w_1 by the predetermined amount, the contacts change over, and terminal 2 becomes connected to resistance R_6 and the voltage suddenly drops to the original low value. Thermistor T_1 now cools and thermistor T_2 heats up increasing the current in w_1 and raising the output voltage as before. At the same time the current through w_2 decreases owing to the cooling of T_1 . The predetermined current difference will presently be obtained again in the opposite direction, when the relay changes over and the process is repeated.

It will be evident that the output obtained at terminals 1 and 2 will be like the usual saw-tooth wave obtained from a conventional relaxation oscillator, but the actual shape of the sloping portions of the waves will depend on the thermistor characteristics and the range of resistance variation employed. These are capable of considerable choice so that a considerable variety of wave forms is possible. The frequency of the oscillations depends among other factors on the rate of heating of the thermistors.

Resistances (not shown) may be inserted in series or in parallel with the heating coils or with the resistance elements for assisting in the control of the frequency and wave form.

If the connections of the upper and lower contacts of a_2 to R_5 and R_6 be reversed, it will be evident that an inverted saw-tooth type wave

will be obtained at the output, that is, a wave in which the voltage is a maximum instead of a minimum after the flyback stroke. This wave will, however, have in general a different form depending on the cooling instead of on the heating of the thermistors.

If thermistors having a positive temperature coefficient of resistance are used, the connection of the windings w_1 and w_2 should be reversed. 10 An inverted wave will be obtained with the contacts a_2 connected as shown in Figure 1. The usual type of wave can be obtained by reversing the connections of a_2 .

A simpler arrangement for producing a similar 15 type of wave employing two directly heated thermistors is shown in Fig. 2. A differential relay B with two windings generally similar to relay A of Fig. 1 has one set of change-over contacts b , the upper contact being closed as shown 20 when the current in winding w_1 exceeds that in w_2 . The windings w_1 and w_2 are connected in series respectively with the resistance elements R_3 and R_4 of the directly heated thermistors T_3 and T_4 to a battery or other source E_2 , the circuit being completed through a common resistance R_7 and through the change-over contacts b . The output terminals 1 and 2 are connected to the extremities of R_7 , and terminal 1 which is connected to the negative terminal of the battery should preferably be connected to earth.

If the battery be supposed to be switched on with the upper contact b closed as shown, the thermistors being assumed to have a negative temperature coefficient of resistance, there will 35 be no current in winding w_1 , and a small current in w_2 since the thermistor T_4 is cold and will therefore have a high resistance. T_4 starts to heat up and its resistance falls, thereby increasing the current in winding w_2 until it becomes 40 sufficient to change over the contacts b . The current in w_2 now becomes zero, and that in w_1 begins to increase due to the heating up of thermistor T_3 . In the meanwhile thermistor T_4 cools and its resistance rises to a high value. 45 When the current in w_1 has reached the operating value, the relay changes over again and the process is repeated indefinitely.

During the period when T_4 is heating up the potential across R_7 (which is obtained at the output terminals 1 and 2) increases steadily from 50 a low value until the relay changes over, when this potential suddenly falls to the original low value which applies when the thermistor T_3 is cool. It then rises as before until the relay 55 changes over again so that a saw-tooth type of wave is obtained as before.

The frequency of the waves depends chiefly on the rate of heating of the thermistors and the form of the sloping portions of the waves will, as 60 before, depend on the shape of the thermistor characteristics. It will be evident that other resistances (not shown) may be included in the circuit if desired for assisting in the control of the operation.

If the thermistors have a positive temperature coefficient a similar result will be obtained if the circuit of Fig. 2 is modified by connecting the thermistors in parallel instead of in series with the corresponding relay windings. In this case each thermistor has a low resistance when cold and will reduce the current through the corresponding winding below the operating value until it has had time to heat up. It will be evident that 70 the operation will be substantially the same as

before, except that an inverted wave will be obtained.

Fig. 3 shows another embodiment of the invention for producing waves more like a series of rectangular waves. In this case the relay is replaced by a four-position stepping switch having an operating winding W and three separate banks of contacts S₁, S₂ and S₃. Each of the contact arms moves one step anti-clockwise when the switch winding W is energized with a current exceeding some predetermined value. The contact arms of banks S₂ and S₃ make contact with one stud in each position, but the contact arm of bank S₁ makes contact simultaneously with the corresponding stud and also with the adjacent stud in the clockwise direction therefrom. The figure shows the three contact arms registering in position 1. When the winding W is next energised, the arms will step to position 2, and so on.

Four similar directly heated thermistors T₁₁, T₁₂, T₁₃ and T₁₄ are connected in series with corresponding equal resistances R₁₁, R₁₂, R₁₃ and R₁₄, and all have one terminal connected to the positive terminal of a battery E₃ or other source of constant potential. The terminals of R₁₁ to R₁₄ are connected respectively to studs 1 to 4 of bank S₁ and through the corresponding contact arm to the negative terminal of the battery and to ground. The junction points of the thermistors and resistances are connected in cyclic order to the studs 1 to 4 of the bank S₃, the contact arm of which is connected to the winding W of the switch and thence to ground. Studs 2 and 4 of bank S₂ are connected respectively to the junction points of T₁₁ and R₁₁, and of T₁₃ and R₁₃. Studs 1 and 3 are each connected to a grounded resistance R₁₅. The contact arm is connected to the output terminal 2, the other output terminal 1 being connected to ground.

In explaining the operation of the circuit, it will be assumed that the thermistors have a negative temperature coefficient of resistance, and that they are all cold when the battery E₃ is first switched on, the stepping switch being in the position 1 as shown.

It will be observed that circuits 1 and 4 are connected to the battery. A small current will flow in each and the thermistors will heat up causing the current to increase. It will be also noted that the potential drop across resistance R₁₁ is applied through bank S₃ to the switch winding W. The current through the winding will accordingly be small at first and should be less than the current required to step the switch.

As the thermistor T₁₁ heats up the current in circuit 1 will increase, as will also the current through the winding W. When this latter current reaches the operating value the switch will move on to position 2. Circuit 4 is disconnected and T₁₄ cools, but circuit 2 is now connected, and T₁₂ being cold has a high resistance and the current in circuit 2 will be small. The winding W is now connected across R₁₂, and as T₁₂ heats up the current through this winding will presently reach the operating value and the switch will step again, and so on.

It will be noted that after stepping to position 2, circuit 1 is still connected to the battery so that T₁₁ continues to heat up and the current in circuit 1 continues to increase. Thus while the switch is on step 2, both thermistors T₁₁ and T₁₂ are heating up but T₁₁ will be hotter than T₁₂ and its resistance will be lower. Thus the potential

drop across R₁₁ will be greater than that across R₁₂.

When the switch is in position 1, the output terminals are connected by bank S₂ across the resistance R₁₅ and the output potential obtained will be zero. When the switch moves to position 2, the output terminals are connected across R₁₁ and an increasing output potential will be obtained while the switch remains in position 2.

10 When the switch moves into position 3, the output potential is again zero. When it moves to position 4, the potential across R₁₃ is obtained, and so on.

The action of the circuit will be more clearly understood from the curves of Fig. 4 which shows in the four upper sets of curves the voltages across R₁₁ to R₁₄ respectively and in the lowest curve the variation of the output voltage obtained at terminals 1 and 2.

15 20 Assuming that the circuit has been started and has reached a steady state of operation, when the switch moves to position 1, the voltage across R₁₁ rises suddenly from zero to a small value and then increases along a curve depending on the

25 thermistor characteristic. When the voltage has reached the value denoted by the point *a*, the switch moves on to position 2, but the voltage across R₁₁ continues to increase since it remains connected to the battery. Circuit 2 is now connected and T₁₂ starts to heat up and the potential across R₁₂ increases along a similar curve.

30 35 When the point *a* is reached the switch steps on again. R₁₁ is disconnected and the voltage drop falls to zero. T₁₃ continues to heat-up while the switch is in position 3 and circuit 3 is connected to the battery. It will now be clear how the process is repeated.

It will be seen that the output terminal 2 is connected only during the positions 2 and 4 of the switch and picks up the potential developed at the terminals R₁₁ and R₁₃ respectively, while this increases along the latter halves *b* of the corresponding curves. It will be evident that the

40 45 wave form obtained at the output will be like the lowest curve in Fig. 4, and is similar to a rectangular wave with the wave tops following a sloping curve determined by the thermistor characteristics.

50 The resistance R₁₅ is provided as a dummy resistance in order that the impedance looking into the terminals 1 and 2 may be the same for all positions of the switch.

It will be evident that studs 1 and 3 of the 55 bank S₂ could have been connected instead to resistances R₁₄ and R₁₂ respectively. In this case the *b* portions of the curve would be also picked up in positions 3 and 1 (see lowest curve Fig. 4) and a saw-tooth type of wave would be obtained

60 By connecting the studs 2 and 4 to the circuits 2 and 4 respectively, the early or *c* portions of the curves can be picked up instead of the *b* portions, and a different wave form will be obtained. Various other arrangements will occur to those skilled in the art.

If the thermistors T₁₁ to T₁₄ have a positive temperature coefficient they may be interchanged with the corresponding resistances R₁₁ to R₁₄ and a similar operation will be obtained.

70 The frequency of operation depends principally on the time taken to heat the thermistors as indicated by the *c* portions of the curves in Fig. 4. This, as well as the wave shape, may be modified by shunting the thermistors with suitable resistances (not shown) or by connecting

other resistances elsewhere in the circuit. Reactive elements or additional thermistors may also be used in this or in either of the other circuits which have been described, for the purpose of modifying the output wave form.

What is claimed is:

1. A generator of cyclically varying currents, said currents varying from one value to a second value relatively smoothly over a long portion of a cycle due to thermistor action and returning quickly to its first value during a relatively short portion of a cycle due to switching action, said generator comprising at least one load resistor, a source of potential, two thermistors, connections for disposing said voltage source, load resistor and one thermistor in series, an output circuit connected across one of the resistive circuit elements, switching means for inter-changing thermistors, that thermistor in circuit being active and undergoing a temperature rise during its operation in circuit, and means controlled by current of said second value through the active thermistor for operating said switching means to inter-change thermistors.

2. The system of claim 1 wherein said switching means includes an electromagnetic relay having normal and off-normal contacts with the thermistors being connected through said contacts, and wherein each thermistor has a relay winding in series therewith, said two windings opposing each other.

3. A generator of cyclically varying currents, said currents varying from one value to a second value relatively smoothly over a long portion of a cycle due to thermistor action and returning quickly to its first value during a relatively short portion of a cycle due to switching action, said generator comprising a source of potential, two load resistors, two thermistors, connections for disposing said voltage source, one load resistor and one thermistor in series, an output circuit connected across one of the load resistors, switching means for inter-changing one thermistor and load resistor unit with the other thermistor and other load resistor, the thermistor in circuit being active and undergoing a temperature rise during its operation in circuit, and means controlled by the current of said second value through the active thermistor for operating said switching means.

4. The system of claim 3 wherein said switching means comprises a differential relay having normal and off-normal contacts for said two thermistors respectively.

5. The system of claim 3 wherein said differential relay has a pair of movable contacts having cooperating fixed contacts, and wherein one movable contact controls the selection of thermistor and wherein the other movable contact controls the selection of load resistor.

6. A generator of cyclically varying currents, said currents varying from one value to a second value relatively smoothly over a long portion of a cycle and returning quickly to its first value during a relatively short portion of a cycle, said generator comprising a pair of load resistors connected to have a common terminal, a thermistor connected to the free end of each load resistor respectively, a differential relay having opposed windings with a common terminal, a connection between the free end of a winding and thermistor respectively, a source of potential between the common winding terminal and load resistor terminal, two movable contacts controlled by said relay, each movable contact having fixed nor-

7 mal and off-normal cooperating contacts, a connection from the outer terminal of each load resistor to a respective fixed contact of said cooperating contacts of one of said movable contacts, an output connection from said one movable contact, a common output terminal at the junction of said load resistors, a connection from the common winding terminal to the other movable contact, a heater for each thermistor, a connection from the common load resistor terminal to one terminal of each heater and a connection from the other terminal of each heater to the other respective fixed contact of said cooperating contacts of the other of said movable contacts.

8 7. A generator of cyclically varying currents comprising a switch having three banks of fixed contacts with a movable contact for each bank, said banks each having an equal even number of successive contacts, the movable contact for the first bank engaging two adjacent fixed contacts while the remaining movable contacts engage a single fixed contact at a time, a branch circuit for each fixed contact respectively of the first switch bank, each branch circuit being connected between its corresponding fixed switch contact and a common terminal, each branch including respectively a load resistor and thermistor in series, a source of potential connected between said common terminal and ground, a connection from the movable contact of the first switch bank to ground, connections from alternate fixed contacts of the second switch bank to ground, a connection for an output circuit to the movable contact of said second switch bank, connections from the remaining fixed contacts of the second switch bank to alternate fixed contacts of the third switch bank, a connection from each fixed contact of the third switch bank respectively to the junction between the load resistor and thermistor in a corresponding one of said branches, the connections to the three switch banks being so made that as the movable contacts progress in the same direction one of the two branches connected through the first switch bank will also be connected through the third switch bank, the entire switching system being so aligned that in any switch position two thermistor branches are energized with one of said branches being connected through the third switch bank and having the same active thermistor branch connected to the output circuit either in that switch position or in the adjacent switch position, every other switch position giving a no voltage output at the second bank, means responsive to a predetermined intensity of current for advancing said switch banks through successive single switching steps, said last-named means being connected between ground and the movable contact of the third switch bank.
